Primary Examiner — Samantha Wood(74) *Attorney, Agent, or Firm* — Boyle Fredrickson S.C.(57) **CLAIM**

The ornamental design for a faucet as shown and described.

DESCRIPTION

FIG. 1 is a top, front, right isometric view of a faucet incorporating my new design;

FIG. 2 is a front elevation view thereof;

FIG. 3 is a right-side elevation view thereof;

FIG. 4 is a left-side elevation view thereof;

FIG. 5 is a rear elevation view thereof; and,

FIG. 6 is a top plan view thereof.

The broken lines in the drawings depict portions of the faucet that form no part of the claimed design.
